Inventor
Thomas Cook,
by Herbert W. Jenner
Attorney.

UNITED STATES PATENT OFFICE.

THOMAS COOK, OF STALYBRIDGE, ENGLAND.

BALING PRESS.

1,426,819.

Specification of Letters Patent. Patented Aug. 22, 1922.

Application filed March 14, 1921. Serial No. 452,169.

To all whom it may concern:

Be it known that I, THOMAS COOK, subject of the King of Great Britain and Ireland, and resident of Stalybridge, in the county of Chester, England, have invented 5 certain improvements in Baling Presses, of which the following is a specification.

This invention relates to improvements in baling presses for use in the baling of all kinds of materials which require to be compressed into a small compass and it consists in the novel construction and combination of the parts hereinafter fully described and claimed.

15 I have found that in compressing material in baling presses that where considerable density is attained it is difficult to remove the compressed bale even when the movable pressed platen is moved away from the bale owing to the ends of the latter or the sides exerting outward pressure against the rigid press box sides or ends and so setting up considerable friction which acts to prevent the easy removal of the bale.

25 In order to avoid the defect referred to my invention consists essentially in the employment of a pivoted and movable side or end of the press box chamber which or end of the press box chamber which during compression can be moved and held 30 by a system of levers and links in a position parallel to the opposite end or side and after compression can be allowed to fall away from the bale so as to allow of the latter to be taken out of the press box quite easily.

35 My invention will be fully described with reference to the accompanying drawing in which—

Fig. 1 is an end elevation of a baling 40 press of the vertical type showing the application of my invention thereto and

Fig. 2 partial front elevation of same.

45 In carrying out my invention I use a sheet metal or other suitable plate *a* usually though not necessarily, extending from the base of the press to the head *b*, such plate also extending between the ordinary side doors *c* of the press, fitting freely against the parts named. Where a sheet metal 50 plate is employed it is usually strengthened at its outer side by being secured to plates *d* of angle or T section so as to resist the internal pressure set up during compressing the bale. At the lower end the plate is 55 provided with pivot pins *e* or a shaft suit-

ably secured to it and mounted in bearings formed in brackets *f* attached to the frame of the press. On the other hand the brackets may be provided with pivot pins passing into bearing brackets fixed to the plate. The latter can move freely about the pivotal points so that the plate can be brought into the vertical position as shown by dotted lines in Fig. 2 which corresponds with its position during the compressing of the bale 60 but allows it to be inclined outwardly when it is desired to take the bale out of the press box. In order to move the plate and hold it in the vertical position whilst compressing is taking place I employ one or more 65 arms *g* fixed upon a shaft *h* mounted in brackets *i* secured to the compressed frame the free ends of said arms carrying bowls or rollers *j* for bearing against the plate. The shaft has also fixed upon it an outwardly extending arm *k* to the free end of 70 which is coupled the upper end of a link *m* the lower end of which is coupled at *n* to a hand lever *o* pivoted at *p* to the machine frame. The arm or operating lever *k* is 75 arranged at an angle to the arms *g*, and it projects upwardly when the arms *g* are horizontal. When the levers and links are in the position indicated in the drawings, 80 the arms *g* are at right angles to the plate *a* so holding the latter in the vertical position and resisting the expansive stresses of the bale material. By moving the hand lever *o* downwardly the arms *g* can be raised so as 85 to allow the plate *a* to assume an inclined 90 position about its pivotal points and so release the bale and allow it to be removed from the press readily.

The arrangement described may be applied to one side of the press when end doors in place of side doors are employed. The arrangement may also be used in conjunction with other types of vertical presses and also to horizontal presses with slight modifications depending upon the character 100 of the press and without departing from the essential feature of my invention.

What I claim as my invention and desire to secure by Letters Patent is:—

The combination, with a press box provided with a side which is pivoted to it at one end, of a rock-shaft journaled in bearings secured to the press box and arranged parallel to its pivoted side, arms secured on the rock-shaft and provided with rollers 110.

for bearing against the pivoted side and holding it in place, an operating lever secured to the rock-shaft and arranged at an angle to the said arms, a hand lever pivoted to the press box and arranged substantially parallel to the operating lever, and a connecting-rod pivotally connecting the two said levers.

In testimony whereof I have hereunto set my hand in the presence of two witnesses.

THOMAS COOK.

Witnesses:

WILLIAM H. TAYLOR,
M. L. RAMSBOTTOM.
